UNITED STATES PATENT OFFICE.

SAMUEL THOMAS YOUNG, OF GLASGOW, KENTUCKY.

APPARATUS FOR FILING AND CANCELING CHECKS OR OTHER PAPERS.

SPECIFICATION forming part of Letters Patent No. 688,769, dated December 10, 1901.

Application filed March 22, 1901. Serial No. 52,307. (No model.)

To all whom it may concern:

Be it known that I, SAMUEL THOMAS YOUNG, a citizen of the United States, residing at Glasgow, in the county of Barren and State of Kentucky, have invented an Improved Apparatus for Filing and Canceling Checks or other Papers, of which the following is a specification.

My invention is an improvement in the class of apparatus for filing and canceling checks, drafts, and other papers in which a series of piercing-points are set upon an inclined frame having a series of steps.

The details of construction are as herein-after described, reference being had to the accompanying drawings, in which—

Figure 1 is a perspective view of the apparatus. Fig. 2 is a perspective view of one of the filing-points. Fig. 3 is a vertical section of a filing-point. Fig. 4 is a perspective view 20 of the split pin constituting part of a filing-point. Fig. 5 is a plan view of one of the triangular portions of the head of a filing-point, the same being shown in the flat. Fig. 6 is a perspective view of such triangular portion 25 bent into the angular form required for attachment to the split pin.

The frame A of my improved apparatus is constructed with two side plates or bars which are inclined at an angle of about forty-five 30 degrees and supported at their upper ends by means of legs a, the said bars being joined transversely by a series of plates or bars a', which constitute the risers of the several steps with which the side bars are provided. Upon 35 each of the several horizontal steps of frame A, I apply a plank or board B, the same being set back from the adjacent riser a' for a purpose hereinafter stated. Upon each of the several supports B, I apply three points C, 40 which serve for canceling and filing checks, drafts, and other papers. These points C are arranged equidistant, and behind each, upon the adjacent riser a', is applied an alphabetical symbol, as shown in Fig. 1. It is to be 45 understood that the frame may be made of any desired size; but in this instance it is so constructed and the number of filing-points is such as to admit of a division of the alphabet, whereby two letters appear behind each 50 point, save in the case of the last one, where four letters appear. Thus, beginning at the top of the frame, the letters "A B" appear be-

hind the first point, the letters "C D" behind the second one, and the letters "E F" behind the third. Thus the several letters are arranged in groups of two and in regular alphabetical succession down to the letters "W X Y Z," which appear behind the last point. Each point has a base-piece c, having screw-holes to provide for permanent and 55 rigid attachment to the several supports B. In such base c is fixed a vertical tube or socket c'. These parts c c' constitute the fixed portion of a point C. The removable portion of the latter is composed of a pin c² and a triangular head c³, composed of two triangular wings c⁴. As shown in Fig. 5, each wing is formed of a piece of sheet-metal of triangular shape, the same being subsequently bent at a right angle along the central longitudinal 60 line, so that it assumes the shape shown in Fig. 6. The head of the pin c² (see Fig. 4) is provided with two cross-slits c⁵, arranged at right angles to each other. Each of the triangular wings c⁴ is set into the slits, so that 65 their vertical angles are adjacent, as shown in Fig. 2, and the same are soldered therein 70 to provide for permanent attachment. The upper ends or points of the two opposite wings c⁴ are bent slightly inward and soldered together, as shown in Fig. 2, so as to form a sharp 75 piercing-point or apex.

As illustrated in Fig. 1, a check or other paper is canceled and filed by pressing it down upon and over the winged head c³ of a 80 point C. If it be supposed that a check bearing a name beginning with "I" or "J" is to be filed, it will be placed upon the point C, which is directly in front of the letters "IJ" upon the second riser a' from the top of the frame A, 85 and so of all other papers. They will be filed by applying them to the points C which are opposite the letters or letter constituting an initial of the name appearing on said papers. It will be seen that by placing the point-supports C back from the risers a' a space is provided 90 for insertion of the fingers beneath the papers when it is desired to remove one or more thereof. It will be further seen that to effect such removal it is only necessary to 95 withdraw upward that portion of a filing-point comprising the winged head and split pin.

By this apparatus the system of canceling

2
and filing checks, vouchers, or any other form of paper is made very convenient, and different items may be practically journalized, which not only facilitates the work of posting 5 to a ledger in alphabetical order, but makes it easy to find the name of a maker or payee or any check on the journal when referring to any past day's work. The apparatus therefore meets the requirements of bankers, who 10 are frequently requested by their customers to refer to the name of the payee of a certain check or the amount thereof. If an index-ledger be used, it is evident that a considerable amount of labor would be saved in posting 15 by reason of the fact that the names on both journal and ledger would appear in alphabetical order and could be posted accordingly without the extra trouble of continuously turning from one side of the ledger 20 to the other. One of the most important features is that any check or voucher can be readily found at any time, so that it is an easy matter to learn the exact standing of any account. The position of the point-supports B adjacent to the risers a' serves to 25 hold the letters, checks, or other papers in such manner that they are prevented from turning around and becoming crossed with each other. In other words, the papers are 30 kept straight and faced one way, so as to be ready for entering when taken from the file.

The boards B are made narrow and spaced from the risers on opposite sides. By making the boards B narrow the fingers of the 35 hand may be run along both sides of them for the purpose of picking up any particular check or collection of checks. The spaces between a board and the riser which is back of it is important in that it allows this operation—⁴⁰ that is to say, it provides an opening for reception of the fingers, so that there is no difficulty in raising a particular check or collection of checks. In further explanation of this feature it may be stated that when

looking through the checks or other papers 45 for the purpose of selecting any particular one if the bottom check or papers should be a little out of line, so as to extend over the front edge of the board B, the hand would be likely to miss the bottom check unless there 50 were a space on the rear side of the board, which allows the check to be conveniently picked by another finger. It will be understood that the fingers run on each side of the board in this operation. 55

What I claim is—

1. The improved apparatus for the purpose specified, comprising a frame or stand having a series of steps, a series of narrow boards B secured on the several steps and each separated from the riser in front and the riser in rear of it by a narrow space, and a series of separable and vertical filing and canceling points secured on said boards, substantially as shown and described. 60

2. The improved filing-point composed of the vertical base-socket, the pin adapted to be set therein and having cross-slits and a head formed of two triangular sheet-metal pieces, each bent centrally lengthwise, and the two parts being set with their angles adjacent and in vertical position, substantially as shown and described. 70

3. The improved filing-point comprising the socket, the removable pin provided with slits as described, the triangular wings bent longitudinally at a right angle, and secured in said slits with their angles adjacent, their upper ends being bent toward each other and soldered together, substantially as shown and described. 75

In testimony whereof I have signed my name to this specification in the presence of two subscribing witnesses.

SAMUEL THOMAS YOUNG.
